UNITED STATES PATENT OFFICE.

HARRY R. RANDLEMAN, OF LONG BEACH, CALIFORNIA, ASSIGNOR OF ONE-HALF TO
ALBERT L. SAYLOR, OF LONG BEACH, CALIFORNIA.

VALVE-SPRING COMPRESSOR.

1,371,643.

Specification of Letters Patent. Patented Mar. 15, 1921.

Application filed January 27, 1920. Serial No. 354,332.

To all whom it may concern:

Be it known that I, HARRY R. RANDLEMAN, a citizen of the United States, residing at Long Beach, in the county of Los Angeles and State of California, have invented certain new and useful Improvements in Valve-Spring Compressors, of which the following is a specification.

The present invention relates to improvements in tools and, more particularly, to a tool adapted to be used for compressing valve springs and the like resilient bodies.

The primary object of the invention is to provide a tool of the above character wherein the gripping jaws are maintained at a fixed angle with respect to each other and to the spring which is engaged, during the complete compressing operation thereby insuring efficiency in operation.

20 A further object of the invention is to provide a valve spring compressing tool wherein the gripping jaws are so mounted with respect to the operating handles whereby the maximum leverage can be obtained 25 and which will permit ready removal of the jaws for the purposes of substitution or repair.

A still further object of the invention is to provide a tool of the character set forth 30 above which is cheap to manufacture, strong and durable and which by reason of its lightness can be operated quickly and easily.

Various other objects and advantages of my invention will become apparent during 35 the continuance of the following description.

In the drawings:—

Figure 1 is a view in side elevation showing my invention in its preferred embodiment; the gripping jaws being shown in an extended position.

Fig. 2 is a view similar to Fig. 1 showing the gripping jaws in a closed or compressed position.

45 Fig. 3 is a view in top plan of one of the gripping jaws.

In reducing my invention to practice I first provide complementary operating handles 10 which are pivotally connected by 50 means of a pin 11 and which by reason of such relation may be operated by gripping the hand engaging portions 12 thereof. At one end the handle portions 10 are offset as at 13 in order to form a fulcrum for the

gripping jaws which will be hereinafter described.

The gripping jaws 14 are pivotally mounted near their forward end upon the offset portion 13 of the handles 10, as at 15. At their rear end the gripping jaws 14 are 60 slightly enlarged as at 16 which enlarged portion is provided with a slot 17 for the reception of the handle portions 10 as clearly shown in Fig. 1. From this it will be observed that while the pivot point of 65 the gripping jaws is forward of the pivot point 11 of the handles, the jaws are prevented from being rocked on the pivot point 15 by reason of the handle portions passing through the slots 17 thereof. At their forward end the gripping jaws 14 are forked as at 18 to facilitate the engaging of the valve spring. The inner edge of the fork portion may be cut away and milled as at 19 in order to insure a better grip.

75 When the parts are in the position shown in Fig. 1 the gripping jaws 14 as well as the hand gripping portions 12 of the handles 10 are in an extended or open position. However, upon pressure being exerted upon 80 the free end of the handle toward each other, the hand gripping portions 12 are, of course, moved in that direction and the gripping jaws will also be moved toward each other until the position shown in Fig. 2 is reached. 85 During movement of the handles 10 the gripping jaws maintain the same angle with respect to each other and to the valve spring thus eliminating the possibility of the spring slipping from engagement with the jaws or 90 becoming broken because of the exertion of unequal pressure thereon.

What is claimed is:—

1. In a tool of the character described, a pair of crossed pivoted operating handles, 95 a pair of jaws pivoted to said operating handles and means whereby said jaws are actuated substantially in parallelism, and forked spring engaging means on said jaws.

2. In a tool of the character described, a 100 pair of crossed pivoted operating handles, a pair of jaws pivoted to said handles forward of their pivots, said jaws having a portion extending rearwardly from their pivots co-acting with said operating handles to 105 actuate them substantially in parallelism, and forked grip means on the forward ends of said jaws.

3. In a tool of the character described, a pair of crossed pivoted operating handles, a pair of jaws fulcrumed on said actuating handles forward of their pivot and having rearwardly extending portions co-acting with said operating handles back of their pivot to maintain said jaws substantially parallel during actuation, and forked seats on the forward ends of said jaws.
- 10 4. In a tool of the character described, a pair of crossed pivoted operating handles, jaws pivoted on said handles forward of their pivotal point and having rearwardly extending portions co-acting with said operating handles back of their pivotal point, the said rearwardly extending portions co-acting with the actuating arm on which the opposed jaw is pivoted, to maintain said jaws in substantially parallel actuating position and forked seats on the forward ends of said jaws.
- 15 5. In a tool of the character described, a pair of crossed pivoted operating handles, jaws pivoted on said handles forward of their pivotal point and having rearwardly

extending portions co-acting with said operating handles back of their pivotal point, the said rearwardly extending portions co-acting with the actuating arm on which the opposed jaw is pivoted to maintain said jaws 30 in substantially parallel actuating position, said co-acting portions comprising slotted members slideable on said handles, and forked seats on the forward ends of said jaws.

6. In a tool of the character described, a pair of pivoted operating handles having offsets at their forward ends, a pair of substantially parallel jaws fulcrumed in said offsets on said actuating handles forward of 40 their pivot and having rearwardly extending portions co-acting with said operating handles back of their pivot to maintain said jaws in substantially parallel actuating position, said co-acting portion comprising slotted members slideable on said handles, and forked seats on the forward ends of said jaws.

In testimony whereof I affix my signature.
HARRY R. RANDLEMAN.
